Primary Examiner — W. A. Teddy Falloway(74) *Attorney, Agent, or Firm* — Birch, Stewart, Kolasch & Birch, LLP(57) **CLAIM**

The ornamental design for a combined lid and container, as shown and described.

DESCRIPTION

FIG. 1 is a front, top, right perspective view of the combined lid and container showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded view showing the lid disconnected from the container.

The broken lines in the Figures are for the purpose of illustrating portions of the combined lid and container and form no part of the claimed design.
